UNITED STATES PATENT OFFICE.

JOHN G. ROTH, OF COLUMBUS, INDIANA.

PUMP.

SPECIFICATION forming part of Letters Patent No. 738,244, dated September 8, 1903.

Application filed April 8, 1903. Serial No. 151,584. (No model.)

To all whom it may concern:

Be it known that I, JOHN G. ROTH, a citizen of the United States, residing at Columbus, in the county of Bartholomew and State 5 of Indiana, have invented certain new and useful Improvements in Pumps, of which the following is a specification.

In cased wells, especially deep-water wells, there is a considerable quantity of sand which 10 is brought up continually with the water and which operates to cut out any bearings which may be used to support rotary parts within the casing and which also operates to allow the moving parts of the pumping mechanism 15 to cut the casing. Instances have been known where the casing has been ruined by such action, and it has become necessary to pull the whole casing and replace sections of it at very considerable expense.

20 The object of my invention is therefore to produce a pump element which may be attached either singly or in series to a rotary shaft which may be lowered into the casing of a well, the element being provided with 25 means to prevent uninterrupted rotation of the water column as it rises and also with means to prevent the cutting of the casing.

The accompanying drawings illustrate my invention.

30 Figure 1 is a vertical section of a well provided with a plurality of my pumping elements. Fig. 2 is an enlarged vertical section of one of the elements. Fig. 3 is a top plan of the parts shown in Fig. 2. Fig. 4 is an 35 under plan of the parts shown in Fig. 2. Fig. 5 is a vertical section similar to Fig. 2 of a slightly-modified form, and Fig. 6 is a perspective view of the retarder.

In the drawings, 10 indicates the casing of 40 a well; 11, the pump-shaft, which is projected into the well substantially to its bottom; 12, suitable bearings for the shaft 11 at the upper end of the well, and 13 a pulley by which the shaft may be rotated. Each pumping 45 element consists of a propeller and a retarder. The propeller consists of a central hub 14, adapted to receive and be secured to shaft 11 at any point. Secured to or formed integral with hub 14 are one or more spiral 50 flights 15, which preferably are of such inclination and length that the upper end of one will lie immediately over the lower end

of the adjacent one. The flights 15 are preferably inclosed in a cylindrical casing 16; but this casing is not absolutely essential, 55 although experience shows that it is preferable, for the reason that it prevents the water from being thrown forcibly against the stationary well-casing at the time when it is receiving its upward impulse. Surrounding 60 cylinder 16 is the retarder-cylinder 17, formed, preferably, of a single sheet of metal the ends of which are not connected and the size of the cylinder such that it must be slightly compressed in order to allow it to enter the 65 casing 10. Secured within cylinder 17 and projecting toward the center thereof are retarding-blades 18, which may be either curved or straight, as may be desired. In the drawings blades 18 are shown beneath the propeller; but they may be arranged above the propeller, if desired. In order to prevent a longitudinal displacement of the retarder-cylinder 17, any suitable means may be provided to extend over the propeller in opposition to 70 the blades 18—as, for instance, downturned lips 19.

In operation a propeller with its inclosing retarder-cylinder 17 is secured to the shaft 11 and lowered into the casing 10, the retarder-cylinder 17 being compressed sufficiently to enter the casing 10 and the propeller lying upon the blades 18 and forcing the retarder-cylinder downward into the well-casing 10. As many of these pump elements as may be 85 desired are secured to a shaft 11, and when they have been lowered into the well-casing the shaft 11 is lifted slightly, so as to bring all of the propellers upward slightly from the retarder-blades 18. The shaft is then rotated 90 in the direction indicated by the arrow.

It will be readily understood that the propeller, which is placed at the lower end of the shaft 11, need not have one of the retarder elements unless desired, or the blades 18 may 95 be omitted, the cylinder 17 then serving merely as a protector for the adjacent portion of the well-casing. The shaft 11 is not provided with any bearings within the well-casing or with any bearings other than at the 100 top end, so that it is free to adjust itself to any inequalities or crooks in the well-casing, the device being substantially self-centered when the shaft is rotated at full speed be-

cause of the action of the propeller-blades within the column of water. There is, however, some wear between the propeller-blades and the adjacent stationary casing, and in 5 my construction this wear is taken by the retarder shell or casing 17, so that if at any time this wear is considerable the operator has merely to withdraw shaft 11, each propeller serving to draw upward with its in 10 closing protector-casing, and this protector-casing may be changed at comparatively little expense. The retarder-blades 18 may be held in place by other means, if desired; but it is much more convenient that these blades 15 be carried by the same element, which serves to protect the well-casing from the wear of the propeller.

I claim as my invention—

1. In a pump of the class described, a propeller element, and a separate protecting-shell longitudinally movable within the well-casing and surrounding the propeller element, and interacting connections between the protecting-shell and the surrounded propeller 20 whereby the shell may be moved longitudinally in the well-casing by longitudinal movement of the propeller.
2. In a pump of the class described, the combination with a propeller element consisting of one or more flights surrounded by a cylindrical casing rotated therewith, of a protector element surrounding the propeller element and longitudinally movable within the well-casing. 25
3. In a pump of the class described, a propeller element, a protecting-shell longitudinally movable within the well-casing and surrounding the propeller element, and retard- 30 ing-blades carried by the protector-shell.
4. In a pump of the class described, the combination with a propeller element consisting of one or more flights surrounded by a cylindrical casing rotated therewith, of a pro- 40

tector element surrounding the propeller element and longitudinally movable within the well-casing, and retarder-blades carried by the protector-shell. 45

5. In a pump of the class described, a propeller element, a protecting-shell longitudinally movable within the well-casing and surrounding the propeller element, and means carried by the protecting-shell to be engaged by the propeller for axial movement. 50

6. In a pump of the class described, the combination with a propeller element consisting of one or more flights surrounded by a cylinder-casing rotated therewith, of a protector element surrounding the propeller element and adapted to lie within the well-casing, and means whereby the propeller may 55 position the protector longitudinally.

7. In a pump of the class described, a propeller element, a protecting-shell adapted to lie within the well-casing and surround the propeller element, retarder-blades carried 60 by the protector-shell, and fingers carried by the protector-shell to engage the propeller element in opposition to the retarder-blades. 65

8. In a pump of the class described, the combination with a propeller element consisting of one or more flights surrounded by a cylinder-casing rotated therewith, of a protector element surrounding the propeller element and adapted to lie within the well-casing, retarder-blades carried by the protector-shell, 70 and fingers carried by the protector-shell to engage the propeller element in opposition to the retarder-blades. 75

In witness whereof I have hereunto set my hand and seal at Indianapolis, Indiana, this 80 23d day of March, A. D. 1903.

JOHN G. ROTH. [L. S.]
